UNITED STATES PATENT OFFICE.

WILLIAM ILE, OF JACKSON, MICHIGAN.

DETACHABLE PLUG.

Application filed May 19, 1925. Serial No. 31,439.

The invention relates to a detachable plug.

The object of the present invention is to improve the construction of detachable plugs and to provide a simple, practical and efficient detachable plug adapted to be screwed into a receptacle or other fixture and to be removed therefrom and provided with a removable cap adapted to permit the plug to remain in such receptacle or fixture and to disconnect therefrom the device or appliance which is supplied with electric current through the plug from the said receptacle or fixture.

A further object of the invention is to provide a detachable plug of this character in which the parts will be rigidly secured in position so that there will be no liability of the same becoming loose through the rotation of the plug or the removal and attachment of the cap thereof.

A further object of the invention is to provide a detachable plug having a cap body and both of molded bakelite or similar insulating material and adapted to reduce the amount of insulating material to a minimum and provided also with ample air space at the points of attachment and at the contacts for protecting the plug and for preventing arcing.

With these and other objects in view, the invention consists in the construction and novel combination and arrangement of parts hereinafter fully described illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a longitudinal sectional view of a detachable plug constructed in accordance with this invention.

Fig. 2 is a similar view taken at right angles to Fig. 1.

Fig. 3 is a plan view of the inner end of the cap.

Fig. 4 is a plan view of the outer end of the body of the plug.

Fig. 5 is a similar view of the inner end of the body of the plug.

Fig. 6 is a detail view of one of the terminals of the removable cap.

Fig. 7 is a plan view of the metallic screw shell.

Fig. 8 is a fragmentary section of the cap illustrating the manner of interlocking the terminals with the cap.

In the accompanying drawings in which is illustrated the preferred embodiment of the invention the detachable plug comprises in its construction an insulating plug body 1 of molded bakelite or other suitable material, a button or end section 2 of similar material and a metallic shell 3 of brass or other suitable material interposed between the button or end section and the plug body 1 and constituting a hollow section of the plug. The metallic shell which is adapted to reduce to a minimum the amount of bakelite necessary for the construction of the plug body is provided with a top wall or flange 4 provided with a central oblong opening 5 receiving an oblong enlargement 6 at the inner face of the end section or button 2 and interlocking the button and the metallic shell against relative rotary movement. The oblong enlargement 6 of the end section or button 2 is of a width less than the width of a button and of a length less than the diameter of the same and the flange 4 of the metallic shell extends entirely around the same as clearly illustrated in Fig. 7 of the drawing. The shell is threaded to screw into a socket or receptacle and its inner end portion 7 is smooth and cylindrical and fits in an annular recess 8 formed by reducing the inner end of the insulating body of the plug. The button 2 is provided with a central opening 9 through which passes a center screw 10 provided at its outer end with a head 11 arranged in a central recess 12 in the outer face of the button 2 and being of polygonal formation to receive a wrench or other tool for screwing its inner threaded end 13 into and out of an interiorly threaded bushing 14 which is embedded in the insulating material of the body 1 of the plug. The interiorly threaded bushing 14 is embedded in the bakelite as an insert during the molding of the body 1 and it is provided at its inner end with an annular flange 15 forming a head and preferably corrugated as shown for securely anchoring the bushing in the molded bakelite or other insulating material and for preventing any loosening and relative rotary movement of the bushing and the body 1. The flange 4 fits

against the inner face of the button 2 and the cylindrical portion 7 embraces the inner end of the body and fits against the shoulder 16 formed by reducing the inner 5 end of the body and the screw 10 when tightened holds the bakelite sections 1 and 2 and a metallic section 3 of the body of the plug firmly together. By providing a hollow intermediate metallic section or shell 10 3 the bakelite may be made in two sections, namely, the button 2 and the body 1 and the button is firmly supported and connected with the body 1 without the necessity of employing an integral connecting portion 15 and at the same time the hollow interior provides an enlarged air space around the parts and thereby insulates the same. The body 1 is provided at its inner end with opposite rectangular recesses 17 which are 20 adapted to receive an arm or tongue 18 formed integral with the hollow shell and arranged interiorly thereof and consisting of the metal cut from the end wall or flange of the same to form the oblong opening 5 25 which receives and interlocks the shell with the button 2. A pair of the recesses 17 is provided to facilitate rigid engagement of the tongue 18 with the body 1 in assembling the parts to the tongue by extending into 30 one of the recesses 17 interlocks the shell with the body and prevents relative rotary movement of the shell and the body 1. The tongue 18 is of a width that fits snugly within the recesses 17 and the shell by means 35 of the tongue and the opening 5 is interlocked with both of the bakelite sections of the plug and holds the same against relative rotary movement.

The body 1 is provided with longitudinal 40 openings 19 and it has curved grooves 20 in its outer end face connecting the openings and forming guides for directing terminals 21 to the openings 19 so that when the terminals 21 are placed in the grooves 20 at 45 any point a partial rotary movement of the terminals and removable cap 22 to which the terminals are secured will carry the said terminals to the longitudinal openings 19. The longitudinal openings 19 receive a center contact 23 and a shell contact 24 consisting of strips of spring metal and provided with protuberances 25 for engaging with oppositely flared openings 26 in the terminals 21 of the cap 22. The terminals 21 are beveled at their side faces at the openings 26 to 50 fit the cup shaped protuberances formed in the contacts 23 and 24 and the beveling of the openings 26 and the cup shaped formation of the protuberances will enable the terminals 21 of the removable cap to be 55 readily moved into and out of engagement with the contacts 23 and 24 of the plug and will provide a firm interlocking connection when the parts are engaged so as to insure 60 a perfect electrical contact. The ends 27 of the terminals 21 are oppositely beveled and the outer ends 28 of the contacts 23 and 24 are bent laterally to permit the terminals 21 to readily pass the ends of the contacts 23 and 24. The longitudinal openings 19 are 70 enlarged at their inner portions by recessing the outer walls at 29 as clearly illustrated in Fig. 1 of the drawings to provide sufficient space for the laterally bent ends of the contacts 23 and 24 when the parts are 75 engaged as shown. The terminals 21 of the removable cap 22 are provided with attaching plates 30 seated in correspondingly shaped recesses 31 formed in the inner face of the removable cap 22. The removable 80 cap 22 is provided with a central opening 32 for the passage of the wires which are connected with the terminals 21 by means of binding screws 33 mounted on the attaching portions or plates of the said terminals 21. The attaching plates are curved at their outer edges to conform to the circular shape of the removable cap which is provided at its inner face with an annular wall 34 forming a space or compartment 35 which not 85 only lessens the bakelite employed in the construction of the cap, but which provides an enlarged air space surrounding the attached portions of the terminals 21 and the ends of the wires connected thereto for both the reduction in the cost of the device and the insulation of the parts. The inner edge of the attaching plate of the terminal is also curved as shown to clear the central opening 32 and the terminals 21 are secured to the removable cap in the recesses 31 by means of screws 36 which engages interiorly threaded bushings 37 embedded in the bakelite of the removable cap as inserts when 90 molding the said cap 22. The bushings 37 are provided with flanges 38 preferably corrugated as shown for anchoring the bushings securely within the bakelite and for effectually preventing any loosening of the bushings through the turning of the screws 36. In order to relieve the attached portions 30 of the terminals 21 of strain and enable each of the terminals to be firmly attached by a single screw each of the plates 30 is 95 provided at one end adjacent to the screw 36 with an integral lug 39 which is engaged in a recess or extension 40. The lug 39 will interlock the plate 30 with the removable cap and relieves the walls of the recesses 31 of strain. By the particular construction and arrangement of the plates 30 of the terminals 21 the latter are securely fastened to the cap and the latter may be removed and replaced without liability of loosening 100 the parts. To facilitate removing and replacing the cap 22 the latter is exteriorly beveled at 41 at the annular wall or flange 34 to provide a groove. This will enable the person removing or replacing the cap to grip 105 the latter under the same and the said cap 110

115 120 125 130

may be firmly and securely held by the person in removing the same from the plug or in replacing the cap thereon.

The center contact is provided at its attached end with an arm 42 extending inwardly from the contact and fitted against the enlargement or extension 6 and pierced by the center screw 10. The shell contact is provided at its inner end with a lug 43 which extends through a slot 44 in the flange 4 of the shell and engages in a recess or seat 45 in the same. The recess or seat 45 is formed by bending or depressing the flange at the slot 44 as clearly shown in Fig. 1 of the drawings and by this construction the lug 43 may be engaged in the seat 45 and the flange will hold the shell contact in position when the parts are secured together by the center screw 10. The shell contact may be permanently secured to the flange or the shell if desired.

The center contact is preferably secured to the end section after the shell has been assembled on the end section. This attaching means of the center contact preferably consists of a sleeve 46 embedded in the end section and lining the central opening thereof and projecting therefrom a sufficient distance to permit the inner end of the sleeve to be expanded in the engagement with the arm of the center contact.

What is claimed is:

1. An electrical attachment plug including an insulating body, an end section of insulating material provided with a polygonal enlargement, a metallic screw shell provided with a flange having an opening receiving and conforming to the configuration of the said enlargement to interlock the shell and the end section, said shell being also provided with a tongue interlocked with the body for holding the parts against relative rotary movement and a center screw connecting the end section and the body and securing the parts together.

2. An electrical attachment plug including an insulating body, an end section of insulating material provided with a polygonal enlargement, a metallic screw shell provided with a flange having an opening receiving and conforming to the configuration of the said enlargement to interlock the shell and the end section, said shell being also provided with a tongue formed integral with the flange by the cutting of the said opening therein and bent into substantially parallelism with the shell and engaged with the body for holding the shell and the body against relative rotary movement and a screw connecting the end section and the body and securing the parts in interlocked relation.

3. An electrical attachment plug including an insulating body provided in its inner end with a plurality of recesses, an insu-

lating end section, a metallic sleeve interposed between the body and the end section and forming a hollow intermediate section and provided with a tongue engaging one of the said recesses to interlock the body and the shell against relative rotary movement and a screw connecting the end section and the body and securing the parts together.

4. An electrical attachment plug including an insulating body provided in its inner end with a recess, an end section of insulating material provided at its inner face with a substantially oblong enlargement, a metallic screw shell provided with a flange having an opening receiving the oblong enlargement to interlock the end section and the shell, said shell being also provided with a tongue extending from the flange longitudinally of the plug and engaged with the recess of the body to interlock the plug and the shell and a screw connecting the end section and the body and securing the parts together.

5. An electrical attachment plug including an insulating body provided in its inner end with a recess, an end section of insulating material provided at its inner face with a substantially oblong enlargement, a metallic screw shell provided with a flange having an opening receiving the oblong enlargement to interlock the end section and the shell, said shell being also provided with a tongue extending from the flange longitudinally of the plug and engaged with the recess of the body to interlock the plug and the shell and a screw connecting the end section and the body and securing the parts together, a center contact secured to the end section by the said screw and a shell contact connected with the flange of the shell.

6. An electrical attachment plug provided with a removable cap having a central opening and having bushings embedded in it at opposite sides of the opening, spaced terminals provided with attachment plates seated within the cap and provided with fastening devices engaging the said bushings, said terminals being also provided with inwardly extending lugs anchored with the cap.

7. An electrical attachment plug including a removable cap provided at its inner face with recesses having an extension and spaced terminals provided with attaching plates seated in the said recesses and having lugs projecting into extensions in the recesses to interlock the terminals with the cap and means for securing the terminals to the cap.

In testimony whereof I have hereunto set my hand.

WILLIAM ILE.
